SUPPORT FOR WALL RECEPTACLES

Filed March 26, 1947

UNITED STATES PATENT OFFICE

2,518,912

SUPPORT FOR WALL RECEPTACLES

Albert G. Lampe, Madison, Wis., assignor to
Gordon Engineering, Inc., Madison, Wis., a corporation of Wisconsin

Application March 26, 1947, Serial No. 737,275

2 Claims. (Cl. 248—27)

1

This invention relates to improvements in means for supporting a receptacle in a wall, and particularly to an improved supporting member which is adapted to support an electrical receptacle such as an outlet box in position in a wall. The invention also relates to the cooperative arrangement of the supporting member with the wall and the receptacle.

Heretofore, it has been common practice in the installation of a receptacle such as an outlet box in a wall opening to hold the receptacle in position as best can be done with one hand while it is being attached to a supporting member, such as a lath, by means of screws with the other hand. Such method of installation is inherently accompanied by difficulties, and it is the primary object of the invention to provide a supporting member which may be quickly and conveniently arranged to support the receptacle in position, whereby the mentioned difficulties are avoided.

It is a further object of the invention to provide a holding means of the character described which is located upon the rearward side of the wall, whereby it is out of sight and out of the way after the receptacle is installed.

It is a still further object of the invention to provide a holding means of the character described, which is simple and economical and contributes considerably to the facility of the installation process.

Other objects and advantages will become apparent as the following description progresses, which is to be read in conjunction with the accompanying drawing in which:

Fig. 1 is a plan view of the improved supporting member in accordance with the present invention;

Fig. 2 is a sectional view taken along broken line 2—2 of Fig. 1;

Fig. 3 is a front elevation showing the receptacle and the cooperating supporting means of this invention, after the receptacle has been installed in an opening in a wall; and

Figs. 4 and 5 are sectional views taken along lines 4—4 and 5—5, respectively, of Fig. 3.

Referring to Figs. 1 and 2, the supporting means of the invention consists of a bracket member, designated generally by the numeral 10, which is composed of a thin, flat, flexible sheet material, such as a flexible metal, for example, iron, aluminum, copper, zinc, or the like.

While the bracket 10 may be of any desired shape, in the preferred form illustrated in Figs. 1 and 2 it is generally rectangular and has a

length somewhat greater than its width. In its final position upon the wall it is arranged with its length extending vertically. It consists of a plate in the general form of a frame or border 12 which surrounds a relatively large opening 14, said opening being of a size and shape such that it is adapted to accommodate an outlet box or any other desired receptacle. A pair of elongated flexible fingers 16 projects inwardly from the edge of each of the two opposite longer side portions of the border 12, said fingers being preferably arranged in staggered relation such that they do not overlap.

If desired, each of the shorter side portions of the border 12 may be provided with a pair of relatively small openings 20 therein which are preferably finished with flanges 22 whereby they are adapted to make threaded engagement with a screw.

20 In connection with the installation of a receptacle, a portion of a wall is shown at 26 in Figs. 3, 4, and 5. An opening 28 is cut into the wall 26 at the desired location of the receptacle, said opening being smaller than the bracket 10 but of a size such that the bracket is adapted to be passed through it. That is, the longer dimension of the opening 28, which is its vertical dimension, is somewhat greater than the shorter dimension of the bracket 10, which is the horizontal dimension of the latter, in the position in which the same is shown in Figs. 1 and 3.

After the opening 28 is formed, the conductors (not shown) which it is desired to connect to the outlet or to a fixture are brought out of the opening and passed through the opening 14 in the bracket 10. The bracket 10 is then passed through the opening 28 while its longer dimension is disposed horizontally. When it is rearward of the wall 26, it is turned until its long dimension extends vertically and it is substantially in the position shown in Fig. 3. In this position, the opening 14 of the bracket 10 is in register with the wall opening 28. The bracket is drawn forwardly until the broad surface of the border 12 rests against the rearward surface of wall 26, and the fingers 16 are then bent forwardly and outwardly in such manner that they rest against the forward surface of the wall and secure the bracket temporarily in place.

50 The conductors are then connected and arranged as described in the receptacle 30 which is shown as being an outlet box of the ordinary open-mouth type. The outlet box is inserted into the aligned openings 14 and 28 and between the opposite pairs of fingers 16. The outlet box

has a length somewhat greater than its width and is arranged with its longer dimension extending vertically. The outlet box has a flange 32 extending vertically from each end thereof, and the box is pushed rearwardly until the flanges 32 rest against the forward surface of wall 26. The three elements, the bracket 10, the opening 28 and the outlet box 30 are then mutually centralized and aligned. The fingers 16 are then bent away from the forward surface of wall 26 and are folded inwardly and backwardly over the forward edges of the outlet box 30 as is most clearly shown in Fig. 4. During this folding operation, the flanges 32 of the outlet box are held in pressure contact against the forward surface of the wall 26 and the border 12 is held in pressure contact with the rearward surface of the wall 26. In this manner, the fingers 16 support the outlet box firmly in position, and further support is unnecessary.

If desired, however, the outlet box flanges 32 may each be provided with one or more openings 34, and the openings 20 in the bracket 10 may be so positioned that they are in alignment with the openings 34 when the parts are in proper position, as shown in Fig. 3. Openings 36 may be provided in the wall 26 in alignment with the beforementioned openings, and screws 38 may be passed through the openings 34 and 36 and screwed into the openings 20 of the bracket 10 to draw the parts together into a rigid assembly.

As is apparent from the foregoing description, the bracket 10 is a simple means for holding an outlet box in position, and serves to facilitate the installation process. It avoids the difficult and awkward task of holding the outlet box by hand at the same time that the installing operations are carried out. In addition, it avoids the necessity for screwing supporting screws directly into the material of the wall, which is the common practice heretofore.

While the bracket 10 is shown as having two fingers 16 extending from each of the opposite longer sides thereof, the number upon each side is not critical and one or more may be provided

as desired. The arrangement, also, may be different from that shown and described. For example, fingers may be provided upon the shorter sides instead of, or in addition to, upon the longer sides.

What is claimed is:

1. A bracket for supporting a receptacle in a wall opening, comprising a flat frame of a size adapted to pass endwise through said wall opening and be turned to engage the rearward surface of said wall surrounding said opening, said frame having an opening therein adapted to accommodate a receptacle located in said wall opening and bearing against the forward surface of said wall, said frame having flexible fingers projecting from portions thereof surrounding said frame opening, said fingers being bendable to engage said receptacle and hold said receptacle in position against said forward wall surface.
2. A bracket for supporting a receptacle in a wall opening, comprising a flat frame of a size adapted to pass endwise through said wall opening and be turned to engage the rearward surface of said wall surrounding said opening, said frame having an opening therein adapted to accommodate an open-mouthed receptacle located mouth forward in said wall opening and bearing against the forward surface of said wall, said frame having flexible fingers projecting from portions thereof surrounding said frame opening, said fingers being foldable around the forward edges of said open-mouthed receptacle to hold said receptacle in position against said forward wall surface.

Certificate of Correction

Patent No. 2,518,912

August 15, 1950

ALBERT G. LAMPE

It is hereby certified that error appears in the printed specification of the above numbered patent requiring correction as follows:

Column 2, line 51, for the word "described" read *desired*;
and that the said Letters Patent should be read as corrected above, so that the same may conform to the record of the case in the Patent Office.

Signed and sealed this 5th day of December, A. D. 1950.
